UNITED STATES PATENT OFFICE

GUNTHER PARIZOT, OF STOCKHOLM, SWEDEN

AIR-DRYING MECHANISM FOR GARMENT PRESSES

Application filed September 22, 1928, Serial No. 307,762, and in Germany September 30, 1927.

In the pressing of clothes or cloth by means of ironing machines, in which the goods to be ironed are treated with steam, these goods become so damp owing to the steam treatment that it has been found necessary to adopt special measures whereby the goods to be ironed can be removed in a dry state from the machine. For this purpose, the press bodies have already been fitted with steam damping and suctioning plants, in order to effect the drying of the material by means of a suctional current. This suctional current passed through the material from the outside inwards, but this however was accompanied by the disadvantage that the drying current naturally turned over the fibres or the pile on the surface of the material and pressed it downwards, thus producing, and more particularly on dark fabrics, the "shininess" which is so much to be dreaded when ironing. In order to eliminate this shininess and as is well known a number of time consuming manipulations had to be carried out which however for the most part adversely affected the smoothness and the shape of the material under treatment. Further, in the process of drying by means of suction, there was always the disadvantage that the current of air used for drying purposes had always to be drawn from the atmosphere in the work room, which as every one knows is very moist owing to the work having to be done on steam presses and is consequently very little adapted for drying purposes.

In accordance with the present invention, the drying of the material is effected, after the ironing pressure has been released, by means of dry compressed air which coming from the press body flows through the material from the inside outwards in such a way that the pile on the material is raised in the direction of the current of air during the drying process, so that the tiresome shininess is avoided. This process has, further, the advantage that the current of air used for eliminating the steam and the moisture from the material can be previously dried as required or, if need be, can be heated, although this is not possible in the familiar suctioning processes. This is important in so far that

the pressing process is very much improved in proportion to the speed and the thoroughness with which the material is cleared of steam and dried, without any bothersome shininess.

Two forms of execution of the subject matter of the present invention are shown, by way of example, on the accompanying drawing and which show the lower part of the press body.

Figs. 1 and 2 afford a top view and a cross section through the lower press body in accordance with the first form of execution, and Fig. 3 is a cross section of this press body in accordance with the second form of execution.

With reference to Figs. 1 and 2, the lower press body in accordance with the first form of execution consists of a heat chamber 1 and a distribution chamber 2 through which after passing through a pipe 3 and a valve 4 the working steam used for damping the material flows. The closing surface of the chamber 1 is fitted with perforations 6 which are covered over by means of a layer of cloth 7. On to this layer of cloth, through which the working steam passes when the material is under treatment, is laid the material 8 which is to be pressed or ironed. The automatic closing valve 4 shuts off the working steam from the material and from a steam pipe 3^a, and is opened by means of a hand or foot lever when damping is to be done. Into the steam pipe 3^a enters a pipe 5 which by means of an automatic closing valve 5^a is connected to a compressed air plant or to a compressor. After the material has been steamed and pressed, the valve 5^a is opened by means of a hand or foot lever, whereupon compressed air enters into the steam pipe 3^a. This air first of all forces any steam that may have remained behind in the pipe 3^a through the material, whilst at the same time the valve 4 is closed, whereby the material is slightly steamed again and the pile on the surface of the material is raised. The current of dry compressed air then removes all remains of steam from the material and dries the latter effectively. In order to have the air as dry

as possible, a moisture absorbing body 9 of any conventional material can be inserted in the air pipe and through which the air must pass, so that by this means it is deprived of moisture.

5 In order to heat the dry air, a heating device 10 in the form of an electrical resistance or of a heating coil can be inserted in the usual way in the current of air.

10 In the second form of execution, shown by way of example in Fig. 3, of the lower press body, 11 is the heat chamber, 12 is the pipe for the steam for steaming the material, 13 the pipe for the compressed air for drying 15 the material, and 14 is the distribution chamber for the working steam and compressed air. Hereby the working steam is fed into the distribution chamber on the one hand, and the compressed air on the other hand, completely separated from one another.

I claim—

A pressing machine including a lower body formed to provide a heat chamber, a 25 foraminous cover for said chamber, a steam pipe leading into said chamber, and a pipe for delivering heated air under pressure opening into the steam pipe below the chamber, a cut-off in the steam pipe arranged beyond the juncture of the air pipe with the steam pipe relative to the pressing machine and a cut-off in the air pipe beyond the juncture of the air and steam pipes whereby the 30 heated air, when admitted, initially forces the steam in the steam pipe into the heat chamber and through the perforated cover and thereafter delivers heated air through such perforated cover.

In testimony whereof I affix my signature.
